UNITED STATES PATENT OFFICE.

OTIS W. WOOD, OF SAN FRANCISCO, CALIFORNIA.

AUTOMOBILE JACK.

Application filed October 29, 1923. Serial No. 671,413.

To all whom it may concern:

Be it known that I, OTIS W. WOOD, a citizen of the United States, residing at San Francisco, in the county of San Francisco and State of California, have invented new and useful Improvements in Automobile Jacks, of which the following is a specification.

This invention relates to improvements in automobile jacks of the type such as comprise a wheeled frame supporting lifting and lowering mechanism and are used in garages and automobile repair shops for the purpose of quickly lifting and moving 10 into various positions automobiles and like vehicles.

One of the objects of the invention is to provide a jack of the character described which is simple as to construction, consists 20 of comparatively few parts, is strong, durable and capable of being quickly and easily operated.

Another object of the invention is to provide a jack of the character described where- 25 in the lifting and lowering or "jack" mechanism is of a simple construction and arrangement and capable of being more quickly, easily and accurately operated than the ordinary mechanism of this nature.

30 Another object is to provide a novel operating mechanism for the jack, which mechanism includes a handle that serves not only as a means for moving the jack bodily into different positions but as a means for operating the lifting and lowering mechanism, it being possible with this arrangement, by grasping a single element as a handle for moving the jack bodily to operate the lifting and lowering mechanism 35 without removing the hand from said element.

Another object of the invention is to provide an automobile jack of the character described which is constructed so that while 40 the jack is being moved into the desired position beneath a portion of the automobile, the lifting and lowering mechanism may at the same time be operated to bring the elevator close to the point where it is to be 45 engaged.

With the above and other objects in view, the invention further consists in the combination of the elements of the parts thereof as illustrated in the accompanying drawings, described in the accompanying specification, it being understood that minor 50

changes in size, detail and proportion of the parts may be resorted to as required without departing from the spirit of the invention as defined in the claims hereto ap- 60 pended.

Referring to the drawings:

Fig. 1 represents a side elevation of a jack constructed in accordance with my invention, said vehicle being broken for the 65 sake of clearness of illustration.

Fig. 2 represents a fragmentary vertical sectional view of the lifting and lowering mechanism.

Fig. 3 represents a bottom plan view of a 70 part of the housing for the lifting and lowering mechanism.

Fig. 4 represents a front elevation of the handle and operating member combined, being shown in part in section. 75

Referring to the embodiment of the invention shown in the accompanying drawings, there is provided a frame generally designated 1, which frame comprises a housing 2, supported by rollers 3 mounted on an 80 axle 4 which is carried by the rear portion of the housing. Extending from the fore part of the housing is a tubular tongue 5, the forward portion of which tube supports an upwardly and outwardly curved bracket 85 6. An upright bearing 7 is provided at the outer end of this bracket and receives the upright swivel pin 8 of a caster 9. On the upper portion of the bracket 6 a short horizontal shaft 10 is journaled and at the outer 90 end of this shaft is attached a sleeve 11 having pivot pins 12 projecting outwardly from opposite sides thereof. Mounted on these pins and held in place by nuts 13 are the forked ends 14 of a combined operating 95 lever and handle 15. On the other end of this member 15 there is provided a short crank 16. This crank 16 serves as a grip when the member 15 is employed as a handle in moving the jack upwardly into different positions. It also serves as a means for rotating the member 15. The shaft 10 may be also rotated by turning the member 15 in a circuitous swinging path. 100

The housing 2 is formed of a bottom casting 17 and an upper or cover section 18. Mounted on bearings 19 supported by the bottom casting 17 is a bevel ring-gear 20 which is secured as at 21 to a hub member 22. This hub member is provided with an 110 internally screw threaded boss 23 in which is mounted the main screw member 24 which

member is tubular and extends downwardly below the gear into a pocket or well 25 therefore. The main screw is adapted to be moved vertically on turning of the gear and also 5 to be turned with the gear without being advanced. The main screw 24 is internally screw threaded as well as externally from its upper end to a point spaced above its lower end and receives an auxiliary screw 27 10 which supports an elevator plate 28, this plate being adapted to engage a portion of an automobile in the lifting and lowering thereof. The gear 19 is driven by a bevel pinion 29 which is fixed to one end of a 15 shaft 30, which shaft extends out through a bearing 31 formed in the upper part of the housing and has a universal joint connection as at 32 with a shaft 33. The shaft 33 extends upwardly and forwardly to the rear 20 end of the shaft 10 at which point it is connected with said shaft by universal joint 34. Thus it will be seen that on rotation of the shaft 10, the shafts 33 and 30 will be turned so that the pinion 29 will rotate the gear 20 25 and operate the lifting and lowering mechanism.

As a means for controlling the operation of the screw members there is provided a sliding detent or key 36 mounted in a sleeve 37 disposed in a bore 38 formed in the lower casting 17. This detent is inclined and adapted at its forward end which is pointed as at 39, to engage in a vertical groove 40 formed in the main screw 24. The key 36 is 30 normally urged in position to engage in said groove by an expansion spring 41 mounted within the sleeve, one end of which spring 41 engages a shoulder 42 on the key and the other end of which engages the inner end of 35 a stuffing box 43 which closes the outer end of the bore and through which stuffing box the key extends. Connected with the outer end of the key is an operating rod 44 which extends upwardly below the shaft 33 and is 40 pivoted as at 45 to an operating lever 46, which lever is in turn pivoted as at 47 on the bracket 6.

To operate the jack, the handle 15 is 45 grasped in order to move the jack into desired position and while so moving the jack, the handle may be turned in order to start the movement of the elevator plate towards the part of the automobile to be engaged. On rotation of the handle 15, the shafts 10, 50 33 and 30 and pinion 29 rotate and cause the gear 20 to rotate in a clockwise direction. Inasmuch as the key 36 engages in the groove in the main screw, said main screw is held against turning and on rotation of the threaded boss 22 being a part 55 of the main gear, said main screw is lifted bodily, moving with it the auxiliary screw 27 and elevator plate 28. This movement is continued until the elevator plate engages 60 the work and may be continued if it is de-

sired to lift the automobile or work but slightly. When it is desired to lift the automobile or work, the operator grasps the lever 46 and swings it towards him so as to retract or withdraw the key from the groove 70 in the main screw. On moving the lever past center, the key will be held disengaged. I claim:

1. A jack of the character described comprising a wheeled frame, a member adapted to engage a part of an automobile to be lifted, mechanism for raising and lowering said member including a shaft directly associated with said mechanism, another shaft adjacent the forward part of the frame, a connecting shaft, universal joints connecting the connecting shaft with the first two shafts and a combined crank and handle member pivoted to the second named shaft. 75

2. An automobile jack of the character described comprising a frame, a lifting and lowering mechanism adjacent one end of the frame, wheels supporting the frame at one end, a bracket extending upwardly from the other end of the frame, a wheel carried by the bracket, means for operating the lifting and lowering mechanism comprising a shaft 85 on the frame adjacent the lifting and lowering mechanism and operatively connected therewith, another shaft carried by the bracket, a third shaft, universal joints connecting the third shaft with the first named 90 shafts and a crank pivoted to the second named shaft. 95

3. An automobile jack of the character described comprising a frame, a lifting and lowering mechanism adjacent one end of the frame, wheels supporting the frame at one end, a bracket extending upwardly from the other end of the frame, a wheel carried by the bracket, means for operating the lifting and lowering mechanism comprising a shaft 100 on the frame adjacent the lifting and lowering mechanism and operatively associated therewith, another shaft carried by the bracket, a third shaft, universal joints connecting the third shaft with the first named 105 shafts, and a member pivoted to the second named shaft and serving as a combined handle for moving the mechanism into different 110 positions and as a crank for rotating said shafts. 115

4. An automobile jack of the character described comprising a frame, a lifting and lowering mechanism adjacent one end of the frame, wheels supporting the frame at one end, a bracket extending upwardly from the other end of the frame, a wheel carried by the bracket, means for operating the lifting and lowering mechanism comprising a shaft 120 on the frame adjacent the lifting and lowering mechanism and operatively connected therewith, another shaft carried by the bracket, a third shaft, universal joints connecting the third shaft with the first named 125 shafts, and a member pivoted to the second named shaft and serving as a combined handle for moving the mechanism into different 130 positions and as a crank for rotating said shafts. 135

5. An automobile jack of the character described comprising a frame, a lifting and lowering mechanism adjacent one end of the frame, wheels supporting the frame at one end, a bracket extending upwardly from the other end of the frame, a wheel carried by the bracket, means for operating the lifting and lowering mechanism comprising a shaft 140 on the frame adjacent the lifting and lowering mechanism and operatively connected therewith, another shaft carried by the bracket, a third shaft, universal joints connecting the third shaft with the first named 145 shafts, and a member pivoted to the second named shaft and serving as a combined handle for moving the mechanism into different 150 positions and as a crank for rotating said shafts. 155

named shafts and a member pivoted to the second named shaft and having a crank portion on its outer end.

5. A jack comprising a frame, a gear rotatable on the frame and having a screw threaded central aperture, means supported by the frame for rotating said gear, a tubular screw threaded member the screw threads of which engage with the screw threads of said aperture and which is provided with internal screw threads, an auxil-

iary screw engaging the internal screw threads of said tubular member, an elevator plate on the upper end of said auxiliary screw, said tubular screw having a vertical groove therein, a detent carried by the frame and withdrawably engaged in said groove, spring means for holding said detent in place and means for withdrawing the detent from engagement of the groove. 15

OTIS W. WOOD.
